DESIGN FOR A RAZOR BLADE

Herbert G. Pressentin, Madison, Wis.

Application October 8, 1941, Serial No. 103,681

Term of patent 14 years

To all whom it may concern:

Be it known that I, Herbert G. Pressentin, a citizen of the United States of America, residing at Madison, in the county of Dane and State of Wisconsin, have invented a new, original, and ornamental Design for a Razor Blade, of which the following is a specification, reference being had to the accompanying drawing, forming a part thereof.

In the drawing:

Fig. 1 is a plan view of a razor blade showing my new design.

Fig. 2 is a side edge view thereof.

Fig. 3 is an end view.

I claim:

The ornamental design for a razor blade, as shown.

HERBERT G. PRESSENTIN.
